UNITED STATES PATENT OFFICE

92,233

DESIGN FOR AN ALPHABET, FOR FORMING MONOGRAMS OR THE LIKE

Olga Dammé, Providence, R. I., assignor to Coro-
Gram Inc., New York, N. Y., a corporation of
New York

Application February 26, 1934, Serial No. 50,882

Term of patent 3½ years

To all whom it may concern:

Be it known that I, OLGA DAMMÉ, a citizen of the United States, and resident of Providence, in the county of Providence and State of Rhode Island, have invented a new, original, and ornamental Design for an Alphabet, for Forming Monograms or the like, of which the following is a specification, reference being had to the accompanying drawing, forming part thereof.

In the drawing:

Fig. 1 represents a design for an ornamental alphabet, which is particularly applicable for

letters formed from metal or other material, the letters Q and X being omitted.

Fig. 2 is a perspective view of the letter A of the alphabet. The letters U and V are identical.

I claim:

The ornamental design for an alphabet, for forming monograms or the like, substantially as shown and described.

Signed at Providence in the county of Providence and State of Rhode Island this 3rd day of February A. D. 1934.

OLGA DAMMÉ.
